UNITED STATES PATENT OFFICE.

ARTHUR W. BERNE, OF NEW ORLEANS, LOUISIANA, ASSIGNOR TO BROWNLEE
W. TAYLOR, OF SAME PLACE.

FARE-COLLECTOR.

SPECIFICATION forming part of Letters Patent No. 431,430, dated July 1, 1890.

Application filed November 9, 1889. Serial No. 329,824. (No model.)

To all whom it may concern:

Be it known that I, ARTHUR W. BERNE, a citizen of the United States, residing at New Orleans, in the parish of Orleans and State of 5 Louisiana, have invented certain new and useful Improvements in a Fare-Collector; and I do declare the following to be a full, clear, and exact description of the invention, such as will enable others skilled in the art to which it applies to make and use the same.

My invention relates to improvements in a fare-collector, in which a case with gravity-plates and a lever-plate trap placed therein are made to operate in conjunction with a 10 coin or fare bag or other receptacle attached thereto. This bag or receptacle is made to lock itself automatically when detached from the case; and the objects of my invention are to provide such a device for use of passenger- 15 conductors, whereby, the fare of a passenger once deposited, it is beyond the control of any one excepting one officer in the treasurer's office. I attain these objects by the mechanism illustrated in the accompanying 20 drawings, in which—

Figure 1 is a front perspective view of my fare-collector complete. Figs. 2 and 3 are rear perspective views of the upper portions of the same detached and partly broken away. Figs. 30 4 and 5 are vertical longitudinal sectional views of the same partly joined together, and Fig. 6 is a plan view of one of the traps.

Similar letters refer to similar parts throughout the several views.

In constructing my device I make a case A of metal or other material, as shown, the top or 35 end portion of which E is funnel-shaped, and is so graduated that it will admit of the passage of the fare either in shape of tickets or coin 40 into the case. Within the case and near the bottom of the funnel E, I place a gravity-trap 1, which is held in position by means of pivots which permit it to swing loosely. When in its normal condition, the trap occupies a substantially vertical position. In close proximity to trap 1 is gravity-trap 2, which is also held in position by pivots and swung loosely 45 within the case.

C is a metal plate, which is pivotally secured 50 within the case A at its upper portion, while

the lower portion is detached from the case, and is operated by means of a handle or thumb-piece D secured thereto and spring 5.

I is a metal case or slide to which bag H is attached by means of the rivets G G.

J is a hasp attached to case I; K, a hasp attached to rear or back of fare-case A.

L is a slot in case or slide I, and into which hasp K enters when case or slide I is adjusted.

3 and 4 are gravity-traps swung loosely on 60 pivots within lower portion of fare-case.

6 are wings, the lower ends of which are beveled or inclined and form the lower portion of metal case.

M is a trap pivotally secured within the slide 65 I by means of the pivots N N, and is provided with a lug, as shown by O, and also a retaining-piece, as shown by P.

Q is a spring, which holds trap M in position when pressure of the wings 6 6 is removed.

R is an ordinary Yale lock, the lock portion of which is provided with a slot S, into which lug O enters when trap M is in its closed position. The trap is unlocked and the lug is released by means of a key inserted in key-hole of lock R. It will thus be seen that when slide I is attempted to be inserted in the metal case the wings 6 will not press back the trap M unless the lug O is released by means of a key inserted in the lock and releasing or unlocking same. When this has been done, the wings attached to the metal case bear upon the trap M and force same against the rear portion of slide or case I; but when the metal case is detached from the bag or other receptacle and the pressure of wings removed the spring Q causes the trap M to resume its former position, where it is automatically locked by the lock R.

In practice the fare is placed into the funnel E and falls upon plate C, and by means of glass B the conductor is enabled to see that the proper fare has been deposited, and when found correct the conductor depresses the lever-plate C by pressure upon thumb-piece D, 95 and permits the fare to descend through the lower portion of fare-case into the locked bag or receptacle H, where it remains locked up. Should it be attempted to pass the fare out of the case after it had been deposited, it will be 100

found that such a procedure will be prevented by the action of the gravity-trap 1, which will close the aperture in lower portion of funnel E. When the fare-case is inverted, gravity-trap 5 2 will rest on lever-plate C, and gravity-traps 3 and 4 will close lower portion of opening of case, thus preventing the removal of fare through the opening E. Thus it will be seen that when the conductor is given his fare-collector, which has been locked by the proper officer, who also furnishes the conductor with funds for making change, the conductor is simply required to present the funnel-shaped end E of fare-collector to each passenger, who 10 15 deposits his fare, which when so deposited virtually comes under the control of the company. After completing his trip the conductor presents his fare-collector to the authorized officer who has charge of the key for unlocking and removing the bag or receptacle H from the metal case, and as said bag or receptacle is removed from the case the wings 20 25 30 35 40 45 50 55 6 release the automatic trap M, and the bag or receptacle thus detached is locked instantaneously, and the said bags or receptacles are carried to the office of the railway company, where the officer who has charge of the key unlocks the bags or receptacles, and having removed the contents leaves the automatic trap M within slide I unlocked, and when in this condition the bag or receptacle is adjust-

ed to the case and locked thereon by a designated officer or employé, and the fare-collector is again placed in the hands of the conductor, and he starts anew on his trip.

35

Having fully described my invention, what I claim, and desire to secure by Letters Patent, is—

1. In a fare-collector, the combination, with a two-part case, of a spring-actuated trap with in one of them and having a lock for securing the same in one position, wings upon the other portion of the case, the ends of which are inclined and engage with and move the trap away from its locked position, and a receptacle detachably secured to the case, substantially as described.
2. In a fare-collector, the combination of a two-part case, a trap pivotally secured in one part of the case, having a lug on one edge and a retaining-piece on its lower side, a lock for engaging with the lower side of the trap and with the retaining-piece, wings upon the other part of the case for operating the trap, and a receptacle detachably secured to the case, substantially as described.

In testimony whereof I affix my signature in presence of two witnesses.

ARTHUR W. BERNE.
